BRIDLE BIT

Leland B. Bergen, Burlingame, Calif.

Application June 30, 1934, Serial No. 733,210

2 Claims.

(Cl. 54—8)

This invention relates to a bridle bit, and particularly to a bit intended for leading and driving.

There are a considerable variety of bridle bits in use for leading and driving horses, such as Mexican bits, curved bits, etc. Bits of this character are particularly intended for hard-bitted and more or less intractable horses, and while they serve the purpose of keeping the horse under control they are usually too severe as there is a tendency to cut, bruise and pinch the corners of the mouth.

The object of the present invention is generally to improve and simplify the construction and operation of bits of the character described; to provide a bit that may be used to rein all types of horses, and in particular, to provide a bit that is more humane to the extent that it will prevent cutting, bruising and pinching of the horse's mouth.

20 The bridle bit is shown by way of illustration in the accompanying drawing, in which—

Fig. 1 is a front view of the bit partially in section.

25 Fig. 2 is a side elevation of the bit partially in section, the section being taken on line II—II of Fig. 1.

Fig. 3 is a perspective view showing the bit applied to a horse.

30 Fig. 4 is a detail horizontal section taken on line IV—IV of Fig. 1.

Referring to the drawing in detail, A—A indicate the cheek-pieces of the bit, B the mouth-piece, and C the straps forming the head stall whereby the bit is held in place. The cheek-pieces are in this instance connected by two cross bars generally indicated at B and D, the bar B forming the mouth-piece and the bar D the hinge bar. The manner in which these bars are connected to the cheek-pieces is an important feature 40 and is accomplished as follows.

45 By referring to Figs. 1 and 2 it will be noted that the upper portion of each cheek-piece is formed in the shape of a ring, such as indicated at 2. These rings are in actual practice an inch or more in diameter, and each ring is provided with a pair of diametrically opposed bearing lugs 3 and 4. These lugs are bent or extended outwardly, as clearly shown in Fig. 1, and pins 5 extending therethrough form pivotal connections between the cheek-pieces and the outer ends of the mouth-piece B as will be clear from a comparison of Figs. 1 and 4. The pivotal connections thus formed will, accordingly, be offset with relation to the inner faces of the cheek-

pieces and cutting or pinching of the corners of the mouth will be avoided.

The upper portion of the rings 2 forming the upper ends of the cheek-pieces are provided with loop-like extensions 6 to which the head stall strap C is attached, a curb strap E being also attached at the same place. Downwardly extending arms 7 are formed on the cheek-pieces and these terminate in pivot pins 8 which extend through the outer ends of the hinge bar D. These pins form pivotal connections between the cheek-pieces and the hinge bar and as the pins 8 align with the pins 5, as shown in Fig. 1, free pivotal movement of the cheek-pieces with relation to the bars B and D is permitted, and inasmuch as the pins 5 are off-set with relation to the inner faces of the cheek-pieces it is obvious that they will have to be angularly disposed and so will the pins 8. It is due to this off-setting of the pins 5 that both sets of pins must be angularly disposed with relation to their respective cross bars and if free pivotal movement is to be permitted the pins 5 and 8 must align. Such alignment is indicated by the dotted lines 9—9. The pins 8 terminate in head members 10, and these serve two functions, first that of securing the hinge bar against endwise removal, and secondly that of forming pivotal supports for eye pins 11 to which the chains 12 are attached. These chains are known as the rein chains as the reins are attached thereto as shown at 14, see Fig. 3.

35 The center portion of the hinge bar carries an eye member 15 and a chain 16 connects this eye member with the curb strap E. This chain may be referred to as the lip hold-down chain as it prevents the horse from lipping the bit, and also prevents the horse from throwing the bit over his nose, and it furthermore holds the bit steady when riding or driving. Each cheek-piece is also provided with a tie bar 17 which serves two functions, first that of reinforcing and strengthening the downward extending side arms 7 of the cheek-pieces, and secondly that of acting as a brush guard, as it prevents brush and the like from 40 getting into the recess indicated at 18.

45 The mouth-piece B may employ a wide cricket and a roller journaled therein, as shown in Fig. 1, or a spoon type mouth-piece, or any other type may be employed; the main feature being 50 that the pivotal connection between the cheek-pieces and the mouth-piece shall be off-set so that when the bit is in the horse's mouth the pivotal connection does not come in contact with the corners of the mouth. This distributes the 55

pressure evenly and prevents cutting and pinching.

It is fact that bits which pinch and cut the corners of the mouth spoil horses by causing them to throw their heads, to fight the bits, and it causes them to become hard-mouthed or cold-jawed. By eliminating the possibility or necessity of such cruel bitting, by the use of the bit here illustrated the horse is made tractable and 10 easily reined, yet there is no weakness in the construction of the bit itself. The hold-down lip chain, indicated at 16, prevents the bit from being thrown over the horse's nose and also keeps the bit steady (prevents it from swinging back 15 and forth). This is also important as it will prevent most horses from throwing their heads.

Besides the humane features produced by this bit, it lends itself to artistic and ornamental design, and if desired, conchas plates such as indicated at 20, may be applied, and while this and other features have been more or less specifically described, I wish it understood that various changes may be resorted to within the scope of the appended claims. Similarly, that the materials and finish of the several parts employed may be such as the manufacturer may decide, or varying conditions or uses may demand.

Having thus described my invention, what I claim and desire to secure by Letters Patent is:—

30 1. A bridle bit comprising a pair of cheek-pieces, said cheek-pieces being ring-shaped, at

their upper ends, a pair of diametrically opposed bearing lugs in each ring, a mouth-piece, pins extending through the bearing lugs and the outer ends of the mouth-piece to form a pivotal connection between the cheek-piece and the mouth-piece, said bearing lugs being bent outwardly with relation to the inner faces of the cheek-pieces so as to bring the pivotal connections in a plane exterior to the said inner faces, a downwardly extending arm on each cheek-piece, a lower hinge 10 bar, and a pivotal connection between the lower end of each cheek-piece and the hinge bar.

2. A bridle bit comprising a pair of cheek-pieces, said cheek-pieces being ring-shaped at their upper ends, a pair of diametrically opposed bearing lugs in each ring, a mouth-piece, pins extending through the bearing lugs and the outer ends of the mouth-piece to form a pivotal connection between the cheek-piece and the mouth-piece, said bearing lugs being bent outwardly with 15 relation to the inner faces of the cheek-pieces so as to bring the pivotal connections in a plane exterior to the said inner faces, a downwardly extending arm on each cheek-piece, a lower hinge bar, a pin extending through each end of the hinge bar and secured to the lower ends of the arms, said pins aligning with the pins extending through the bearing lugs and both sets of pins being disposed on an angle with relation to the 20 inner faces of the cheek-pieces.
